COLLAPSIBLE POCKET TOOL

Werner G. Salg, Oak Park, Ill.

Application November 23, 1946, Serial No. 712,031

5 Claims. (Cl. 132—76.2)

1

This invention relates to improvements in collapsible hand-tools and more particularly, pocket tools, such as knives, nail files and the like.

The main object of the invention is to provide a simple and efficient tool of the type aforesaid which may be embodied in a part of another device, such as a pocket comb, equipped with a spring clip adapted to engage the upper edge portion of the exposed wall of the pocket which receives the tool and wherein a portion of said clip performs another function and the member which secures the clip in place constitutes also the pivot of a blade or the like which is rotatable through an arc from the position wherein it is usable to a collapsed and housed position.

Another object of the invention is to provide the blade of the structure with a formation which cooperates with the bottom wall of the recess within which the blade is housed when in its collapsed position, and with the said pivot thereof, to retain the blade firmly in its usable position without resort to the use of a spring.

A further object of the invention is to provide a structure of the type referred to wherein a portion of the said clip cooperates with the formation of the blade to retain the latter firmly but yieldingly in its collapsed position.

A suitable exemplary embodiment of the invention is illustrated in the accompanying drawings, wherein:

Fig. 1 is a view in side elevation of a comb, the back of which is equipped with a recess to receive the blade of the structure and is constructed in accordance with the invention.

Fig. 2 is an enlarged view in end elevation, looking at the right hand end of Fig. 1.

Fig. 3 is a top plan view of the structure.

Fig. 4 is a central, vertical longitudinal sectional view of the same showing the blade of the structure turned to the outer limit of its movement and showing in dotted lines the position of said blade when in use.

Fig. 5 is a fragmentary plan sectional view, on an enlarged scale, taken on the line 5—5 of Fig. 4.

Fig. 6 is a vertical transverse sectional view taken on the line 6—6 of Fig. 5.

In the instance illustrated, the back portion 1 of a comb 2, which constitutes the handle of the tool of this invention, is equipped midway between its side faces with a longitudinal recess 3 which extends through one end thereof and terminates at a point spaced from its other end.

The tool element 4 of the structure, in the instance illustrated, consists of a blade of suitable metal and provides a fingernail file surface 5 and

2

a terminal fingernail cleaning formation 6, it being obvious that said blade may be replaced by a conventional pocket knife blade and also that the blade down may be equipped also with a longitudinal cutting edge.

The depth of the recess 3 is slightly less than the width of the blade 4. Said blade 4 is equipped, preferable, with a straight edge 7 which, when the blade is disposed in position for use, as shown in dotted lines in Fig. 4, bears upon the straight bottom wall of the recess 3.

The other edge 8 of the blade 4 is spaced normally very slightly from the straight bottom wall of the recess 3, when the blade 4 is positioned, as shown in Fig. 1, and projects along its said edge portion 8 from the recess 3.

Adjacent the inner end of the recess 3, the side walls of the latter are provided with recesses 9 for the passage of finger tips into engaging relation to the blade 4 to effect its movement to the full line position of Fig. 4.

Said blade 4 is equipped adjacent to its semi-circular extremity 10 with a longitudinal slot 11 which extends slightly angularly to said blade edge 7 from the end of the slot 11 which is arcuately concentric with said end 10 of the blade toward the pointed end of the latter.

The angle at which said slot 11 extends to the blade edge 7 is preferably about ten degrees, more or less.

A resilient metal clip comprising two arms 12 and 13 is secured to one side face of the member 1 by means of a rivet 14 which extends through both side walls of the recess 3 at a point spaced from the open end of said recess and through the slot 11 of the blade 4 and at an elevation above the opposed bottom wall of the recess 3 such distance that when the blade 4 is disposed at the outer limit of its movement, as shown in Fig. 4, the meeting point of the blade edge 7 with the semi-circular end 10 of the blade will be spaced slightly from the bottom wall of said recess 3, and when the blade 4 is in said full line position of Fig. 4, said rivet 14 constitutes the pivot of said blade 4.

The blade 4 is then moved to the dotted line position of Fig. 4, approximately, and thus the slot 11 cooperates with the rivet 14 and the opposed point in the bottom wall of the recess 3 to wedge the blade firmly against the latter throughout an appreciable portion of its length.

The arm 12 of the clip, which is secured to the member 1 by the rivet 14 is equipped at its extremity with a formation 15 which is equipped

with an arcuate convex surface 16 disposed at the outer end of the flange 17 of said arm 12.

The wall of the member 1 to which said arm 12 is secured, is provided with an opening through which said flange 17 and the formation 15 thereof projects, the said arcuate surface 16 of the formation 15 being disposed normally and yieldingly in the path of the blade 4 and is moved outwardly against the spring action of said arm 12 by the edge 7 of the blade 4 as the latter is swung to the position of Fig. 1, the said arcuate surface portion 16 being thus caused to spring into the other end portion of the slot 11 of the blade 4 as the latter attains the position of Fig. 1.

When in its last-named position, the rivet or pivot element 14 of the blade 4 will be disposed in the same end portion of the slot 11 as shown in Fig. 4, the length of said slot 11 being such that when the arcuate convex formation is engaged in said slot, the blade 4 is held yieldingly against movement toward the open end of the recess 3 of the member 1 as well as against pivotal movement.

The blade 4 is provided with fingernail receiving recesses 18 and the arm 13 of the clip is equipped with a semi-spherical formation 19, the convex surface of which bears normally yieldingly against the member 1.

I claim as my invention:

1. A pocket tool comprising a handle member equipped with a blade receiving recess open at one end and with an opening through a side wall of the latter, a resilient pocket wall engaging clip comprising an outer and an inner arm, the latter equipped with a terminal L-shaped flange projecting through said opening, a rivet passing through said handle member and spanning said recess adjacent one end thereof and securing said inner arm of said clip to said member, a blade equipped adjacent one end thereof with a longitudinal slot through which said rivet extends and constitutes a pivot for said blade when the latter is disposed at the outer limit of its movement relative to said member, said pivot and slot being positioned relative to the bottom wall of said recess to cause said blade to be non-rotatable when moved longitudinally inwardly from said outer limit of its movement.

2. A structure, according to claim 1, wherein said L-shaped flange of said clip is equipped with a convex surface portion projecting into said handle recess into the path of said blade and engages in the slot thereof when the same is disposed at the inner limit of its movement.

3. A pocket tool comprising a handle member equipped with a blade receiving recess open at one end and with an opening through a side wall of the latter, a resilient pocket wall engag-

ing clip comprising an outer and an inner arm, the latter equipped with a terminal L-shaped flange projecting through said opening, a rivet passing through said handle member and spanning said recess adjacent one end thereof and securing said inner arm of said clip at a point between the ends thereof to said member, the outer arm of said clip being longer than and overlying said inner arm and bearing at its terminal end portion upon said handle, a blade equipped adjacent one end thereof with a longitudinal slot through which said rivet extends and constitutes a pivot for said blade when the latter is disposed at the outer limit of its movement relative to said member, said pivot and slot being positioned relative to the bottom wall of said recess to cause said blade to be non-rotatable when moved longitudinally inwardly from said outer limit of its movement, said L-shaped flange being equipped with a convex surface portion projecting into said handle recess into the path of said blade and engages in the slot thereof when the same is disposed at the inner limit of its movement.

25 4. A pocket tool comprising a handle member equipped with a blade receiving recess having a substantially straight bottom wall and being open at one end, a resilient member mounted upon a wall of the said member and equipped with a terminal L-shaped flange projecting into an opening in a wall of said recess, a blade equipped with a semi-circular end and with a longitudinal slot adjacent the latter with one end disposed concentric with said semi-circular end, a rivet 30 passing through the said resilient member adjacent its other end and through said handle member and the slot of said blade to secure said resilient member rigidly and said blade pivotally to said handle member, said blade being movable inwardly longitudinally from the outer limit of its pivotal movement to a position wherein said blade is held against pivotal movement, the innermost end portion of said L-shaped flange being equipped with a convex surface projecting 35 said recess and into the slot of said blade when the latter is turned to the inner limit of its pivotal movement.

5. A structure, according to claim 4, wherein the said blade is equipped with a straight edge 40 disposed substantially parallel with the bottom wall of said recess when said blade is turned to the outer limit of its movement and wherein the slot of said blade is disposed angularly to said straight edge for causing the latter to bear upon the bottom wall of said recess when the same is moved longitudinally inwardly from the outer limit of its movement.

WERNER G. SALG.
